US00D853704S

(12) **United States Design Patent** (10) **Patent No.:** **US D853,704 S**
(45) **Date of Patent:** **** Jul. 16, 2019**

(54) **SHOE OUTSOLE**(71) Applicant: **NIKE, Inc.**, Beaverton, OR (US)(72) Inventors: **Kenneth Link**, Portland, OR (US);
Chris Jury, Portland, OR (US);
Sebastien Mermet, Portland, OR (US)(73) Assignee: **NIKE, Inc.**, Beaverton, OR (US)(**) Term: **15 Years**(21) Appl. No.: **29/631,393**(22) Filed: **Dec. 29, 2017****Related U.S. Application Data**

(63) Continuation of application No. 29/593,540, filed on Feb. 9, 2017, now abandoned.

CLAIM

The ornamental design for a shoe outsole, as shown and described.

DESCRIPTION

FIG. 1 is a front perspective view of a shoe outsole showing our new design;

FIG. 2 is a bottom view thereof; and,

FIG. 3 is a rear perspective view thereof.

The broken lines showing the remainder of the shoe represent unclaimed subject matter and form no part of the claimed design.
